UNITED STATES PATENT OFFICE.

GEORGE W. JENINGS, OF ROCHESTER, NEW YORK.

REFRIGERATOR.

SPECIFICATION forming part of Letters Patent No. 553,855, dated February 4, 1896.

Application filed January 17, 1895. Serial No. 535,183. (No model.)

To all whom it may concern:

Be it known that I, GEORGE W. JENINGS, of Rochester, in the county of Monroe, in the State of New York, have invented new and 5 useful Improvements in Refrigerators, of which the following, taken in connection with the accompanying drawings, is a full, clear, and exact description.

My invention relates to improvements in 10 refrigerators, and is particularly applicable for use with refrigerator-vehicles for transporting dressed meats, butter, poultry, eggs, and similar articles, and has for its object the production of a device which is readily 15 placed in its designed position and practically and effectively supports dressed meats from the top wall of the vehicle and the remaining articles upon the floor or bottom wall without permitting access of the accumulat- 20 ing water thereto; and to this end it consists, essentially, in the general construction and arrangement of said frame, the supports therefor, and its connections to the body.

In describing this invention reference is 25 had to the accompanying drawings, forming a part of this specification, in which like letters indicate corresponding parts in all the views.

Figure 1 is an isometric view of the end of a refrigerator-car provided with my invention 30 and having portions of its top, end, and front side walls broken away for more clearly illustrating said invention. Fig. 2 is an enlarged vertical sectional view showing the supporting-frame, the intermediate bars or strips for 35 engaging the top face of said frame, the adjacent portion of the top wall of the body to which said bars or strips are secured, and the supports for holding said frame in its operative position, intermediate portions of the 40 frame and supporting-wall being broken away. Fig. 3 is a detail sectional view taken on line 3 3, Fig. 2, showing adjacent portions of the supporting-frame, the hinged connection for securing the same to the supporting-body and the supports for said frame. 45 Fig. 4 is an isometric view of the detached connection shown at Fig. 3, the intermediate portion thereof being broken away. Fig. 5 is a detail sectional view taken on line 5 5, Fig. 50 2; and Fig. 6 is a transverse section of a por-

tion of a car provided with my supporting-frame arranged for use as an inner door.

Refrigerators, and particularly refrigerator-cars, are usually used for preserving dressed meats, butter, poultry, eggs, and similar articles, and as at present constructed are unprovided with a supporting-frame which may be practically and effectively used either at the top of the refrigerator for supporting the dressed meats or at its base for supporting 55 other articles.

My invention has for its object the production of a device which may be used for this purpose and may be readily and quickly placed in either its upper or lower position. 60

A represents the body of the refrigerator, which may obviously be stationary or movable, and at Fig. 1 I have shown a portion of one extremity of a refrigerator-car, which may be of any desired form, size, and construction. In constructing cars of this character they are provided with a suitable inlet a at one end of their top walls for the entrance of ice and a transverse bar or beam a' supported within the car beneath and in proximity to its top wall a². This bar or beam forms a support for the ice-box, which I have not deemed it necessary to herein illustrate or describe, as the same forms no part of my present invention. 75

B B represent my improved supporting-frames, which preferably consist of racks composed of separated longitudinal and transverse bars b b' suitably secured together, and obviously the frames are formed with a 80 series of slots b³ interposed between the bars b. The frames B B are arranged one in advance of the other with their adjacent edges substantially in contact and the end edge of the outer frame substantially in contact with 85 the contiguous face of the bar or beam a' when in elevated position, and consequently endwise movement of said frames is prevented. As illustrated in the drawings, the frames B B are preferably half the width of 90 the car in order that their adjacent edges b⁴ may engage each other and prevent lateral movement of said frames, and to facilitate this result said edges b⁴ are inclined so as to 95 lap with each other. 100

At Fig. 1, as I have illustrated but a part of a car, I have shown in full lines only the two outer or end supporting-frames, one in its upper and the other in its lower position. 5 I have, however, indicated by dotted lines the adjacent ends of the frames abutting against the outer or end frames, and it will be obvious to one skilled in the art that each side of the car is provided with a series of 10 supporting-frames of sufficient length and width to prevent endwise and lateral movement of said frames when all are in their upper or lower position.

If desired the combined length or width of 15 the frames may be only part of that of the car, and in such event suitable transverse or longitudinal bars or beams may be used to form an abutment for the adjacent edges of the supporting-frames, as will also be readily 20 understood by one skilled in the art.

The inner side edge of each frame B is secured to the body A by a connection or bar C, which is preferably adjustable lengthwise, and consists of separate sections $c'c'$ 25 having their adjacent extremities lapped and provided with guides c^2 . The upper and lower extremities of the sections $c'c'$ are hinged, respectively, to the adjacent side walls, as a^3 , of the body A and the supporting-frames B, 30 and said walls and frames are provided with suitable hinged pieces or leaves c^3 secured thereto by fastening means c^4 for connection to the sections $c'c'$. When the supporting-frames are in their lower position upon the 35 bottom wall or floor a^4 of the body A, the connections C are extended to their utmost limit. When elevating the frames to their upper position they are rocked outwardly upon the hinged joint formed between the sections c' 40 and said frames and are then elevated until the connections C are sufficiently shortened, whereupon the frames are swung upwardly upon the joints formed between the sections c and the adjacent side of the body A and are 45 thus elevated above said connections.

The connections or bars C support the outer edges of the frames B when in their upper position, and suitable supports D are utilized for preventing downward movement 50 of the free or outer edges of said frames. These supports D preferably consist of arms hinged at their upper ends to eyes d projecting from the top wall a^2 of the body A, and having their lower ends movable through the 55 slots b^3 and provided with shoulders d' for engaging the adjacent portions of the frames B. As clearly illustrated at Fig. 2, the shoulder d' engages the connections or bars C, which are arranged beneath the frames B, 60 instead of directly engaging said frames.

Upward movement of the frames B when in their upper position is prevented by intermediate bars or strips E having their upper edges secured by hinges e to the top wall a^2 65 and their lower edges movable into engagement with the top faces of said frames, as

clearly seen at Fig. 2. When the frames B are in their lower position the bars or strips E are swung upwardly and engage suitable supports F consisting preferably of yielding arms 70 having their upper ends secured by suitable fastening means f to the top wall a^2 of the body A and their lower ends provided with engaging shoulders f' . The bars or strips E are also provided with stops F' for preventing 75 undue movement of the supports D and holding said supports in an elevated position when the bars or strips E are swung upwardly, as illustrated by dotted lines at Fig. 2.

At Fig. 6 I have shown a body A^{10} provided 80 with an opening a^{10} in its side wall a^{11} partially closed by a frame B^{10} which, when used as illustrated, forms an inner door for said opening. This frame B^{10} may be secured to the side wall a^{11} by a lengthwisely-adjustable 85 connection or bar exactly similar to the connection C, previously described; but I have shown a connection C^{10} , which is particularly applicable for use therewith. This connection consists of a section c^{10} secured to the frame B^{10} by suitable fastening means c^{11} and provided with guides c^{12} and a second section c^{13} , which is hinged at c^{14} to the side wall a^{11} , 90 and is movable lengthwise of the guides c^{12} as the frame is elevated. When the frame 95 B^{10} is in its lower position the connection C^{10} is extended to its utmost, and when the frame is sufficiently elevated vertically it swings upwardly upon the hinge c^{14} to the position illustrated by dotted lines at Fig. 6. 100

The operation of my invention will be readily understood upon reference to the accompanying drawings and the foregoing specification, and it will be readily apparent that its supporting-frames are readily placed in either 105 their lower or upper positions and operate to practically and effectively support dressed meats, butter, poultry, eggs, &c. It is obvious, however, that they may be used to support other articles, and that my invention 110 is not restricted for use with refrigerator-cars, as it is equally applicable for stationary 115 refrigerators. It is also obvious that the supporting-frames may be raised to their upper position for conveniently arranging them in the upper part of the refrigerator, even though it is not intended to use them as supports when in such position.

Having thus fully described my invention, what I claim as new, and desire to secure by 120 Letters Patent, is—

1. The combination of a body, a substantially vertical connection or bar adjustable lengthwise and having one extremity connected to the body, and a supporting-frame having one edge hinged to the connection and its opposite edge movable above the former edge in proximity to the connection, as said frame swings on its hinge, substantially as and for the purpose described. 125

2. The combination of a body provided with a transverse bar or beam, a series of substan- 130

tially vertical connections or bars adjustable lengthwise and having their upper extremities connected to the body, and a series of supporting-frames arranged with their contiguous end edges in contact, and the end edge of the outer frame substantially in contact with the bar or beam, said frames having corresponding edges hinged to the connections, and their opposite edges movable above the former edges in proximity to the connections as the frames swing on their hinges, substantially as and for the purpose specified.

3. The combination of a body provided with a hinge-piece, a substantially vertical connection or bar adjustable lengthwise and arranged in proximity to the side wall of the body with its upper extremity hinged to said hinge-piece, and a supporting-frame having its edge nearest the connection or bar hinged thereto and its opposite edge movable above the former edge in proximity to the connection, said supporting-frame being movable above the plane of the connection or bar as said connection swings on its hinge for elevating its lower end, substantially as and for the purpose set forth.

4. The combination of a body, a substantially vertical connection or bar adjustable lengthwise and having one extremity connected to the body, a supporting-frame having one edge hinged to the connection and its opposite edge free and movable above the former edge in proximity to the connection as said frame swings on its hinge, and a movable support for holding the frame in its elevated position, substantially as and for the purpose described.

5. The combination of a body provided with a hinge-piece, a substantially vertical connection or bar adjustable lengthwise and arranged in proximity to the side wall of the body with its upper extremity hinged to said hinge-piece, a supporting-frame having its edge nearest the connection or bar hinged thereto and its opposite edge movable above the former edge in proximity to the connection, said supporting-frame being movable above the plane of the connection or bar as said connection swings on its hinge for elevating its lower end, and a movable support or arm for holding the frame in its elevated position, having one end hinged to the top of the body and its opposite end provided with a shoulder for engaging the frame, substantially as and for the purpose set forth.

55. 6. The combination of a body, a substantially vertical connection or bar adjustable lengthwise and having one extremity connected to the body, a supporting-frame having one edge hinged to the connection and its opposite edge movable above the former edge in proximity to the connection as said frame swings on its hinge, and an intermediate bar or strip interposed between the supporting-frame and the adjacent wall of the body, and having one edge hinged to the body, and its opposite edge detachably engaged with the

supporting-frame, substantially as and for the purpose set forth.

7. The combination of a body provided with a hinge-piece, a substantially vertical connection or bar adjustable lengthwise and arranged in proximity to the side wall of the body with its upper extremity hinged to said hinge-piece, a supporting-frame having its edge nearest the connection or bar hinged thereto and its opposite edge movable above the former edge in proximity to the connection, said supporting-frame being movable above the plane of the connection or bar as said connection swings on its hinge for elevating its lower end, and an intermediate bar or strip secured to the top wall of the body and interposed between said top wall and the supporting-frame, when in its elevated position, substantially as and for the purpose described.

8. The combination of a body, a supporting-frame secured to the body, an intermediate bar or strip interposed between the supporting-frame and the adjacent wall of the body, and having one edge hinged to the body, and its opposite edge detachably engaged with the supporting-frame, and a yielding support or bar provided with a shoulder for engaging the intermediate bar or strip and holding the same in its inoperative position, substantially as and for the purpose specified.

9. The combination of a body, a supporting-frame secured to the body, an intermediate bar or strip secured to the top wall of the body and interposed between said top wall and supporting-frame, and a movable support or arm having one end hinged to the top wall of the body in proximity to the intermediate bar or strip and its opposite end provided with a shoulder for engaging the frame and holding the same in its operative position, substantially as and for the purpose described.

10. The combination of a body, a supporting-frame, a lengthwisely-adjustable connection or bar having one extremity connected to the body and the other extremity hinged to the frame, an intermediate bar or strip interposed between the frame and the adjacent wall of the body, and a movable support or arm having one end hinged to the body in proximity to the intermediate bar or strip and its opposite end provided with a shoulder for engaging the frame and holding the same in its operative position, substantially as specified.

11. The combination of a body, a supporting-frame, a lengthwisely-adjustable connection or bar having one extremity connected to the body and the other extremity hinged to the frame, an intermediate bar or strip interposed between the frame and the adjacent wall of the body, a movable support or arm having one end hinged to the body in proximity to the intermediate bar or strip and its opposite end provided with a shoulder for en-

gaging the frame and holding the same in its operative position, and a stop secured to said bar or strip for engaging the support or arm, substantially as and for the purpose described.

5 In testimony whereof I have hereunto signed my name, in the presence of two at-

testing witnesses, at Rochester, in the county of Monroe, in the State of New York, this 4th day of January, 1895.

GEORGE W. JENINGS.
